UNITED STATES PATENT OFFICE

HARRY W. VICKERY, OF LYNN, MASSACHUSETTS, ASSIGNOR TO GENERAL ELECTRIC COMPANY, A CORPORATION OF NEW YORK

CIRCUIT CONTROLLER

Original application filed August 2, 1926, Serial No. 126,464. Divided and this application filed December 27, 1929. Serial No. 416,977.

This application is a division of my application, Serial No. 126,464, filed Aug. 2nd, 1926. The invention relates to circuit controllers. More particularly it relates to controllers of a type especially adapted for use in connection with traffic signals. Among the objects of my invention are, to provide a circuit controller adapted for use in connection with a plurality of signals and having means for regulating their time intervals and their relation with respect to each other.

The means for accomplishing the objects of my invention are hereinafter more fully set forth and claimed, reference being had to the accompanying drawings, in which Fig. 1 shows the controller of my invention in perspective; Fig. 2 is a longitudinal section through the commutator cylinder of the controller; Fig. 3 is a section approximately across the central portion of the device taken through the carriage which carries the contact roller that operates in conjunction with the commutator cylinder; Fig. 4 is a section just to the right (Fig. 1) of the knob by means of which the carriage shown in Fig. 3 is adjusted; and Fig. 5 is a diagrammatic layout of the circuit connections employed in connection with the device.

Referring more in detail to the drawings, in Fig. 5 the source of power is represented by the lines 2 and 3. From this line current is drawn for operating the traffic signals R, A, and G, for operating the motor M, and for operating the relays 4, 5 and 6. The function of the motor is to rotate the shaft 7, and through gears a commutator cylinder which is constructed with two metallic sections 8 and 9, which sections are diagonally cut and insulated from each other and from the frame, as indicated in Fig. 2. Associated with the commutator is a brush 10 in the form of a roller on the end of the shaft 11 (see Fig. 3). This brush device is mounted on a carriage 12 (see Fig. 1), which is adapted to be slid along the rods 13 and 14 through the medium of the knob 15 and rack 16. The shaft 11, Fig. 3, extends through the carriage 12 and is journaled in a metal bearing 17, which passes through the frame 12 of the carriage and is in intimate metallic

contact with a metal block 18. This block is provided with a metallic frame 19, to which latter a spring 20 is pivotally secured by means of the pin 21. Between the spring 20 and the frame 19 is a compression spring 22, which serves to maintain the spring 20 in contact with a pin 11' which passes through the shaft 11 just below the spring 20, thus insuring good electrical connection between the spring 20 and the roller 10. 60 Roller 10 is mounted on a metallic pin on the lower end of the shaft 11, which pin serves as a bearing for the roller 10.

As shown in Fig. 3, the forward end of the spring 20 is provided with a contact 23 which operates in connection with a corresponding contact 24 secured to a pin 25. The arrangement is such that connection is caused to be made and broken between the contacts 23 and 24 by the commutator as it rotates 70 relatively to roller 10. As shown in Fig. 3, the contacts are in engagement and therefore a circuit connection is closed between the spring 20 and the pin 25, and consequently, also between the pin 25 and the metallic block 75 18. Pin 25 is connected with a conductor 26, and block 18 is connected with a conductor 27.

Referring to the commutator, the segment 8 is provided with a brush 28, see Figs. 2, 90 4 and 5. This brush is connected with conductors 29 and 30, Fig. 5. The other segment 9 of the commutator is provided with a pair of brushes 31. Two brushes are provided merely for insuring contact between the conductor 32 and the commutator element 9. The brushes 31 rub along the end of the cylinder 9, as indicated in Figs. 5 and 2, while the brush 28 is arranged to rub along the side of the cylinder 8. 90

As shown in Fig. 5, the signals R, A and G are all connected on one side to the conductor 3, while on the opposite side they are connected respectively with contacts 33, 34 and 35 of the relays 4, 5 and 6. Each of these relays 4, 5 and 6 is preferably in the form of a solenoid, and each is therefore provided with a plunger 36. Each plunger carries a pair of circuit closing contacts each insulated from the other; for example, 100

the relay 4 is provided with contacts 37 and 38, relay 5 with contacts 39 and 40, and relay 6 with contacts 41 and 42. The contact 38 has associated with it a pair of contacts 43 and 44, the contact 40 a pair of contacts 45 and 46, and the contact 42 a pair of contacts 47 and 48. Associated with the contact 37, there are contacts 33 and 49; with contact 39 there are contacts 34 and 50; and with contact 41 there are contacts 35 and 51. Therefore, as indicated, when the relay 4 is energized the contacts 33 and 49 are electrically connected through the contact 37, and connection broken between contacts 43 and 44. However, when the relay 4 is deenergized, connection is broken between contacts 33 and 49, and connection is closed between the contacts 43 and 44 by the contact 38. When the relay 5 is energized both connections controlled by the contacts 39 and 40 are closed as shown in Fig. 5 and when the relay is deenergized both connections are opened. The operation of the relay 6 is the same as that of the relay 4, that is, when this relay is energized contact 41 closes the circuit between contacts 51 and 35, and contact 42 breaks the circuit between contacts 47 and 48, and when this relay deenergizes the reverse condition results.

I will now describe more in detail the operation of the circuits. Assume that the contact roller 10 is in engagement with the segment 8 when the switch X is first closed. Motor M is started over conductors 53 and 53' on one side and conductor 3' on the other. Also the relay 6 will become energized over conductors 53 and 27, contact 10, segment 8 and conductor 29, with the result that one of the two circuits of the relay 4, that is, the circuit between the contacts 47 and 48, is opened. At the same time the circuit for the signal G is closed between the contacts 35 and 51, thus causing the operation of the signal G over conductor 53.

As the motor continues to operate the edge of segment 8 advances toward contact 10 and finally contact 10 descends into the space between the two segments 8 and 9. As a result contacts 23 and 24 are closed, thereby causing the energization of relay 5 over conductors 53 and 27, contacts 23 and 24, and conductor 26 on one side and conductor 26' on the other. Relay 5 closes the circuit for the signal A at the contacts 50 and 34 from the line 2, over conductor 53 on one side and back to line 3 on the other, thereby operating the signal A. At the same time the relay 5 closes a holding circuit for the relay 6 by way of conductor 53, contacts 46 and 45 of relay 5, contacts 43 and 44 of relay 4 and conductors 30 and 29, thus holding the relay 6 energized after the segment 8 leaves the contact 10 and preventing its

deenergization until the segment 9 strikes the contact 10.

When the segment 9, advancing, strikes the contact 10, it closes a circuit through the relay 4 by way of the segment 9 and the contact 10 over conductors 53, 27 and 32, and winding of relay 4, to line 3 thereby energizing relay 4. At the same time the contacts 23 and 24 are separated causing the deenergization of relay 5. As a result of the energization of relay 4 the holding circuit for the relay 6 is broken between the contacts 43 and 44, thereby retiring the signal G. At the same time the circuit for the signal R across conductors 2 and 3 is closed by way of the contacts 33 and 49, whereupon the signal R appears. Since the circuit of relay 5 is interrupted as indicated, and since it therefore deenergizes, the signal A retires. The deenergization of the relay 5 also breaks the holding circuit of the relay 6 at a second point, that is, between the contacts 45 and 46.

As the segment 9 continues to advance under the contact 10 the signal R persists. When the space between the segments 9 and 8 is reached, the contacts 23 and 24 again engage, energizing the relay 5 and once more operating the signal A by closing the circuit between the contacts 34 and 50. At the same time a holding circuit for relay 4 is established by way of conductor 53, contacts 46 and 45, conductor 57, contacts 48 and 47, conductor 55, winding of relay 4 and conductor 26'. The holding circuit prevents the deenergization of the relay 4 until segment 8 reaches contact 10. When segment 8 strikes the contact 10 the energizing circuit for the relay 6 is again closed as before by way of the contact 10 and the segment 8. At the same time the circuit for the relay 5 is broken between the contacts 23 and 24, when the contact 10 rides upon the segment 8, and causes their separation. The result of this last is that the signal A is again retired and the holding circuit for relay 4 is broken, thus retiring signal R. The energization of relay 6 on the other hand causes the appearance at the same time of the signal G and the rupture of the holding circuit for the relay 4 at the second point that is between the contacts 47 and 48.

The above operation of the relays 4, 5 and 6 is repeated as long as the motor continues to rotate the segments 8 and 9, thus operating the signals R, A, G in the order described, the signal A appearing just before the signal G is retired and appearing also just before the signal R is retired. In other words, signal A is operated twice during each cycle of operation in which the G signal is operated once and the R signal is operated once.

For the purpose of regulating the speed of the motor, I provide the rheostat S in connection with the motor, and by this means the length of the signals can be varied without changing the relation of their time intervals.

However, as is well known, the relation of the time intervals should be changed as the traffic conditions change and for this purpose I provide means for changing the ratio of the 5 time intervals. This may be accomplished by moving one of the segments with respect to the other and by adjusting the roller 10 axially along segments 8 and 9. With the arrangement shown I provide means for moving 10 the segment 9 with respect to the segment 8. As indicated in Fig. 2, the segments 8 and 9 are mounted on cores 60 and 61 of insulating material. These cores are mounted on the shaft 7' which is driven by the motor M 15 and arranged to rotate therewith. The core 60 is permanently secured to the shaft 7'. This core is also provided with a rod 62, which is embedded in the core 60. The core 61 is provided with a similar rod 63 which is embedded in the core 61. In the core 61 there 20 is a bore into which the rod 62 projects and within which it may slide, while in the core 60 there is a bore into which the rod 63 projects and in which it may slide. With this 25 arrangement the segments 8 and 9 are caused to rotate with the shaft 7', but the segment 9 may be adjusted along the shaft 7'. The core 61 is further provided with a collar 64 of insulating material which collar is mounted 30 at the end of the core 61 in such a manner that the core 61 may rotate relatively to the collar 64. The collar 64 is provided with a threaded bearing through which the threaded shaft 65, see Fig. 1, passes. This shaft terminates in a knob 66 and is mounted to rotate in the frame of the device. By rotating the knob 66, the collar 64 may be caused to travel back and forth, that is, to the right or to the left, Fig. 2, with the result that 35 the core 61, together with the commutator 9, may be adjusted back and forth, even while the motor M is rotating.

By adjusting commutator segment 9 relatively to commutator segment 8, the distance between the adjacent ends of the segments may be increased and decreased. This serves to increase and decrease the time during which roller 10 is between the two segments and hence the time during which 40 contact 23 which controls the amber signal is in engagement with contact 24. By moving the carriage 12 to the left or to the right the time interval during which roller 10 is in contact with segments 9 and 8 may be varied, thereby adjusting the length of the red and green signals relatively to each other. It will thus be seen that by adjusting segments 9 and 8 relatively to each other the duration of the amber signal is varied and 45 by adjusting the roller 10 axially relatively to segments 9 and 8 the respective duration of the red and green signals is adjusted, the amber remaining the same.

Referring to Fig. 1, the rheostat S is provided with a knob 67, by means of which the

speed of the motor is regulated as previously explained. On the left hand end of the shaft 7 there is provided a worm gear 68, which meshes with the gear 69. The gear 69 is mounted on the same shaft with a worm 70 75 70, which in turn meshes with the gear 71 on the right hand end of the shaft 7' for driving the latter.

As shown in Figs. 1 and 2, the whole apparatus is assembled about a suitable base and frame, thus forming a compact portable unit on which for the purpose of connecting the controller with the source of power and with the signals, suitable terminals 72 are mounted. In connection with the construction, there 80 is provided means for indicating the adjustment of the carriage 12 and the adjustment of segment 9 relatively to the frame. For this purpose a scale plate 73 is attached to the frame and adjacent to it is a strip 74 85 which is attached at one end to head 64, as is indicated at 75, so that the strip moves with the head and segment 9. The other end of strip 74 cooperates with scale plate 73 to indicate the adjustment of segment 9. Carried by carriage 12 is a pointer 76 which cooperates with the scale plate to indicate the adjustment of the carriage. The lower portion of the pointer is bent around under strip 74 to form a support for the free end of strip 90 95 74. This is indicated more clearly in Fig. 3.

The operation as described is such, therefore, that the R and A signals overlap at one time and the G and A signals overlap at another. But if desired such overlap can obviously be prevented by opening the switches 58 and 56. The result of this is that the holding circuits for relays 4 and 6 are left open and the R, A and G signals can only operate in sequence. 100 105

Therefore, by means of a central controller, Fig. 2, a set of signals, or a plurality of sets of signals, one set for each intersection along the highway, may be controlled from a common point, from which point the time intervals of the various signals of each intersection may be varied. By the provision of relays the energizing circuits of the signals themselves, such as signals R, A, G, may each be made quite short and of moderate 110 115 size. Otherwise, to avoid excessive drop in voltage due to the comparatively high volume of current necessary for operating the signals over long circuits much larger conductors would be necessary. Furthermore, 120 the provision of a central control means capable of varying the time interval of each of the signals makes it possible to provide a minimum number of elements. Otherwise, and in order to accomplish the same result, a 125 much larger number of parts would be necessary in order to insure an adequate number of variations in the signals.

While I have elected to describe my invention in connection with the specific forms of 130

apparatus illustrated in the drawings, I do not wish to be so limited inasmuch as I contemplate under the claims contained herein variations and modifications within the spirit of the invention.

What I claim as new and desire to secure by Letters Patent of the United States is:

1. In a signal controller, a pair of commutator segments mounted to rotate about an axis, said segments being disposed in a slanting direction between two parallel planes extending transverse said axis, a brush mounted between said planes to make contact with the segments alternately as they rotate about said axis, and means for moving one of the segments with respect to the other along said axis for varying the width of the space between such segments whereby the ratio of the time interval of engagement between the brush and one of the commutators is adjusted.

2. A signal controller comprising a commutator mounted on a shaft, means for rotating said shaft and commutator, said commutator comprising a pair of metal segments, each segment having a surface concentric with said shaft, said segments overlapping each other along a region located between two planes parallel to each other and extending transverse said shaft, said segments being insulated from each other, a brush mounted to engage said segments alternately at a point between said planes, means for adjusting said brush along said shaft between said planes, means for adjusting one of said segments with respect to the other along said shaft and a circuit contact under the control of the brush, the segments of the commutator being separated in the path of the brush between said planes and a depression between the segments whereby the controller operates as a cam to raise and lower the brush to open and close said contacts.

3. A circuit controller comprising a commutator, said commutator being in the form of a cylinder mounted about an axis, said cylinder being cut in two along a plane extending transverse of and slanting with respect to said axis to form two commutator segments overlapping each other between two parallel planes, the latter extending across said axis, said segments being insulated from each other, and means for adjusting said segments with respect to each other along said axis.

4. A circuit controller comprising a commutator, said commutator being in the form of a cylinder mounted about an axis, a brush for said commutator, said brush being located between two parallel planes extending across said axis, said cylinder being formed of two metal sections separated from each other between said planes and along a plane slanting across said axis, said brush being mounted to engage said segments alternately along a

plane perpendicular to said axis as the cylinder rotates, and adjusting means for moving one of said segments along said axis to vary the distance between the two segments along said perpendicular plane.

5. A circuit controller comprising a commutator, said commutator being in the form of a cylinder mounted about an axis, a brush for said commutator, said brush being located between two parallel planes extending across said axis, said cylinder being formed of two metal sections separated from each other between said planes and along a plane slanting across said axis, said brush being mounted to engage said segments alternately along a plane perpendicular to said axis as the cylinder rotates, adjusting means for moving one of said segments along said axis to vary the distance between the two segments along said perpendicular plane, and means for adjusting said brush along said axis between said parallel planes to vary the position of the perpendicular plane of engagement between the brush and the segments.

6. A circuit controller comprising a commutator, said commutator being in the form of a cylinder mounted about an axis, a brush for said commutator, said brush being located between two parallel planes extending across said axis, said cylinder being formed of two metal sections separated from each other between said planes and along a plane slanting across said axis, said brush being mounted to engage said segments alternately along a plane perpendicular to said axis as the cylinder rotates, adjusting means for moving one of said segments along said axis to vary the distance between the two segments along said perpendicular plane, and means for adjusting said brush along said axis between said parallel planes to vary the position of the perpendicular plane of engagement between the brush and the segments, said brush being mounted to move in one direction when it engages one of said segments and in the reverse direction when it leaves said segment, and a circuit interrupter under the control of said brush whereby a circuit may be opened and closed as the brush is moved back and forth by the commutator.

7. A circuit controller comprising a commutator, said commutator being in the form of a cylinder mounted about an axis, a brush for said commutator, said brush being located between two parallel planes extending across said axis, said cylinder being formed of two metal sections separated from each other between said planes and along a plane slanting across said axis, said brush and cylinder being mounted to rotate one with respect to the other about said axis whereby the brush may engage the segments alternately in cycles along a plane perpendicular to said axis, and means for moving one of said segments with

respect to the other along said axis to vary the distance between the segments along said perpendicular plane to vary the ratio of the intervals of engagement of the brush and the segments.

8. A circuit controller comprising a commutator, said commutator being in the form of a cylinder mounted about an axis, a brush for said commutator, said brush being located between two parallel planes extending across said axis, said cylinder being formed of two metal sections separated from each other between said planes and along a plane slanting across said axis, said brush and cylinder being mounted to rotate one with respect to the other about said axis whereby the brush may engage the segments alternately in cycles along a plane perpendicular to said axis, and means for moving the brush along said axis to vary the plane of engagement between the contact and the segments whereby the ratio of the intervals of engagement between the brush and the segments may be varied.

9. A circuit controller comprising a commutator, said commutator being in the form of a cylinder mounted about an axis, said cylinder being cut in two along a plane extending transverse of and slanting with respect to said axis to form two commutator segments overlapping each other between two parallel planes, the latter extending across said axis, said segments being insulated from each other, means for adjusting said segments with respect to each other along said axis, and index means for indicating the amount of movement between the segments.

10. A circuit controller comprising a commutator, said commutator being in the form of a cylinder mounted about an axis, a brush for said commutator, said brush being located between two parallel planes extending across said axis, said cylinder being formed of two metal sections separate from each other between said planes and along a plane slanting across said axis, said brush being mounted to engage said segments alternately along a plane perpendicular to said axis as the cylinder rotates, adjusting means for moving one of said segments along said axis to vary the distance between the two segments along said perpendicular plane, means for adjusting said brush along said axis between said parallel planes to vary the position of the perpendicular plane of engagement between the brush and the segments, and index means for indicating the degree of movement of the brush along said axis.

11. A circuit controller comprising a commutator, said commutator being in the form of a cylinder mounted about an axis, a brush for said commutator, said brush being located between two parallel planes extending across said axis, said cylinder being formed of two metal sections separated from each other be-

tween said planes and along a plane slanting across said axis, said brush being mounted to engage said segments alternately along a plane perpendicular to said axis as the cylinder rotates, adjusting means for moving one of said segments along said axis to vary the distance between the two segments along said perpendicular plane, means for adjusting said brush along said axis between said parallel planes to vary the position of the perpendicular plane of engagement between the brush and the segments, and index means for indicating the amount of movement of the brush along said axis and the amount of movement of one of said segments with respect to the other.

In witness whereof, I have hereunto set my hand this 23rd day of December, 1929.

HARRY W. VICKERY.
